[57] CLAIM

The ornamental design for a lockable housing for secur-

ing electrical plugs, substantially as shown and described.

DESCRIPTION

FIG. 1 is a top rear, left side perspective view of a lockable housing for securing electrical plugs showing my new design;
FIG. 2 is a top plan view thereof;
FIG. 3 is a front view thereof;
FIG. 4 is a bottom plan view thereof;
FIG. 5 is a rear view thereof;
FIG. 6 is a left side view thereof;
FIG. 7 is a right side view thereof;
FIG. 8 is a left side view thereof showing the container open;
FIG. 9 is a top, front, right side perspective view of an alternative embodiment of that shown in FIG. 1;
FIG. 10 is a top plan view of the alternative embodiment;
FIG. 11 is a front view of the alternative embodiment;
FIG. 12 is a bottom plan view of the alternative embodiment;
FIG. 13 is a right side view of the alternative embodiment;
FIG. 14 is a left side view of the alternative embodiment;
FIG. 15 is a rear view of the alternative embodiment; and
FIG. 16 is a cross-sectional view taken along the lines **16—16** of FIG. 11.
